ELECTRICAL PLASMA-JET TORCH

Erich Muehlberger and Robert P. De La Vega, Costa Mesa, Calif., assignors to Geotel, Inc., Amityville, N.Y.

Filed Oct. 12, 1970, Ser. No. 25,429

Term of patent 14 years

Int. Cl. D8—05

U.S. Cl. D8—30

FIG. 1.

FIG. 2.

FIG. 1 is an isometric view of an electrical plasma-jet torch embodying our new design;

FIG. 2 is a top plan view thereof;

FIG. 3 is a side elevation, illustrating the side not shown in FIG. 1;

FIG. 4 is a rear elevation;

FIG. 5 is a bottom plan view; and

FIG. 6 is a fragmentary sectional view on line 6—6 of FIG. 3.

We claim:

The ornamental design for an electrical plasma-jet torch, substantially as shown.
